UNITED STATES PATENT OFFICE.

MAX E. BIERACH, OF MILWAUKEE, WISCONSIN.

MACHINE FOR MAKING ANTITACKS.

SPECIFICATION forming part of Letters Patent No. 630,845, dated August 15, 1899.

Application filed December 16, 1897. Renewed February 16, 1899. Serial No. 705,693. (No model.)

To all whom it may concern:

Be it known that I, MAX E. BIERACH, a citizen of the United States, residing at Milwaukee, in the county of Milwaukee and State 5 of Wisconsin, have invented new and useful Improvements in Machines for Making Antitacks, of which the following is a specification.

My invention relates to improvements in machinery for manufacturing that class of 10 fasteners known as "antitacks," which consist of a strip of metal bent and pointed at the ends and which are used as label, stamp, or seal holders and for a variety of similar purposes.

15 The object of my invention is to provide adjustable mechanism whereby the antitacks may be pointed, bent, stamped, and separated from a strip of sheet metal in a single machine having coöperative and successively- 20 acting parts.

In the following description reference is had to the accompanying drawings, in which—

Figure 1 is a plan view of my invention, showing the same as it is when in operation. 25 Fig. 2 is a vertical longitudinal section view drawn on line X X of Fig. 1. Fig. 3 is an elevation of the discharge end. Fig. 4 is an end view of the actuating-cam of the feed-roller. Fig. 5 is a side view of the same. 30 Fig. 6 is a plan view of the supporting-frame with the bed removed. Fig. 7 is a cross-section of the frame-bed and the adjusting mechanism drawn on line y y of Fig. 1, but with the operating mechanism removed. Fig. 35 Fig. 8 is a left-hand side view of the bender-head with a portion broken away to show the construction of the spring-actuated roller-supporting arms. Fig. 9 is a side view of the denter. Fig. 10 is a detail top view of the 40 denter and the die with which it registers.

Like parts are identified by the same reference-figures throughout the several views.

A frame 1 is provided with a bed formed in two parts or blocks 2 2', each adjustably 45 keyed to the frame by means of the downwardly-projecting portions 3, Figs. 2 and 7, engaged in slots 4 and arranged to be locked therein at any desired point of adjustment by means of bolts 6 and plates 5, the latter 50 being arranged to engage the frame on each side of the slots and adapted to form a bearing for the head of the bolt. The parts 2 2'

of the bed are separated by means of a right and left screw-threaded shaft 7 near each end, the lock-bolts 6 being first loosened to 55 permit the bed-blocks to move in the slots 4. When separated, the parts are rigidly supported against vibration by means of wedges 8, which are forced upwardly between the blocks by means of screws 9. 60

The material from which the antitacks are made consists of a strip of metal 10, which is fed longitudinally over the bed between the feed-rollers 11 into the path of the forming-tools, as hereinafter explained. The bed is 65 adjusted in each case to correspond to the width of the strip, that portion which extends between the tools being narrowed to conform to the width of the uncut portion of the strip.

The tool-actuating shafts 12 and 12' are 70 supported, respectively, from the bed-blocks 2 and 2' and actuated from the source of power through the drive-wheel 13, shaft 14, worm 15, and gear-wheels 16, the latter being keyed to the shafts 12 and 12'. 75

The initial tool comprises a cutter or punch head 17, one on each side, which is provided with recesses in which the punches 18 are removably secured by screws 19, coöperating with a holding-disk 20, bearing upon the edges 80 of the punches to afford a lateral support. The punches are provided with tapered and notched ends 21, which are adapted to register in counterpart notches in a die-plate 22, located in a recess in the bed. The edges of 85 the strip 10 of the material are engaged by the punches and cut to form teeth or points 23, as shown in Fig. 1, the material being moved forward intermittently as the teeth are cut. The shafts 12 12' are also provided 90 with bender-heads 24, provided with sockets 25, in which are located arms 26, the latter having studs 27, which engage in slots 28 in the head to retain the arms in the sockets, with springs 29 adapted to hold the arms 95 normally with the studs engaging the outer ends of the slots. The arms are provided at their outer ends with antifriction-rollers 30, which engage the points 23, formed by the punches in the material, and bend them 100 downwardly, as shown in Fig. 1. After the points are bent downwardly they are creased or crimped longitudinally by means of a crimping-punch 31, which registers with a die

32, screwed to the side of the bed, the punch-rod 31^a being actuated by the rollers 33, located in the outer ends of the arms 33^b, projecting from a hub 33^c. The rollers engage 5 upon the curved plate 33^d, attached to the outer ends of the rods 31^a.

35 are springs for retracting the crimping-punches as soon as their supporting-rods are released by the actuating-rollers.

10 The material after leaving the punches is passed under a printing-plate 36, which is actuated as hereinafter explained, and over the shear-bar 37.

38 is a separating-knife pivoted at 39 and 15 provided with an extended arm 40, which is connected by a retracting-spring 41 with the floor or other suitable point of support to hold the knife normally in a position with its edges above the shear-bar. A downward 20 movement is intermittently communicated to the knife from the shaft 12 through the eccentric 42 and roller 43, the latter being supported on a trunnion projecting from the front end of the knife-blade. The downward 25 movement of the knife separates the antitacks from the strip 10 of material, cutting the same transversely between the successive points 23, which are formed in its sides. The knife having completed its downward movement, it is returned to its normal position by the retracting-spring 41.

The motion of the knife-arm 40 is communicated to the printing-plate through the adjustable connecting-rod 44, lever 45, stud 46, 35 vertically-sliding plate 47, spring 48, and supporting-plate rod 49, the plate 47 being supported in a frame 50, projecting upwardly from the bed. The lever 45 is provided with a slot 51, in which the stud 46 engages, thus 40 permitting the plate to slide freely in the bracket without cramping. The motion of the lever 45 is also communicated to an inking-roller 52 through the stud 46, sliding plate 47, lug 53, link 54, and curved lever 55, 45 the latter being pivoted at 56 to the frame 50. With the extreme movement of the lever 45 downward upon the lug 46 the printing-plate 36 is forced downwardly and the inking-roller is carried outwardly over the 50 rotary ink-supply plate 57, and with the reverse movement of said lever the printing-plate is raised and the roller is carried under the same to distribute the ink upon the type. While in this latter position, the roller is 55 given a short oscillatory movement by means of intermediate projections 58 on the eccentric plate 42, which actuates the knife and printing mechanism.

It will be observed that the various operating-tools are arranged to act simultaneously and at regular intervals, but that their action is successive in relation to any given portion of the strip. It is therefore necessary that the feed should be intermittent, and 60 for accomplishing this result I have provided the shaft 12' with an eccentric plate 59, which bears at intervals upon the roller 60, located

on one arm of an elbow-lever 61, the motion of which is communicated to the lower feed-roller 11 through the rod 62, crank 63, pawl 64, and ratchet 65, the motion being regulated by the proportion of the parts to correspond in time with the intervals between the action of the tools and in distance to the width of the finished antitacks.

66 is a retracting-spring for withdrawing the rod 62 and its connected parts after the movement caused by the eccentric plate 59 is completed.

It will thus be observed that the strip of 80 material as fed by the feed-rollers is punched to form the tack-points, the pointed ends bent by the rollers of the bending-heads and crimped or dented by the denter, the uncut portion of the material stamped by the printer, 85 and then separated by the knife between the successive points to form the completed antitacks ready for the market. All the tools are actuated from the two shafts 12 and 12' in such a manner as to coöperate each with the other in an intermittent simultaneous action upon the various parts of the work. The bed being adjustable, I am enabled to use the same device for strips of different widths by substituting feed-rollers, printing mechanism, cutting-knives, &c., of the proper size to correspond with the width of the strip and the size of the antitacks to be formed.

While I have shown and described the various parts of the printer and printing mechanism in the construction used, I do not claim the specific construction thereof in this application, as this construction may be independently used for other purposes, and I therefore expressly reserve the same as the 105 subject-matter of a future application.

What I claim as new, and desire to secure by Letters Patent, is—

1. A machine for making antitacks, comprising a bed, shafts supported at the sides thereof, a set of feed-rollers arranged to feed strips of material intermittently over the bed, and a set of operating-tools actuated from said shafts and adapted to serrate the edges of the material, bend down the points or teeth of the serrated edges, and to separate the material transversely, substantially for the purpose set forth.

2. A machine for making antitacks, comprising a bed, shafts supported at the sides thereof, a set of feed-rollers arranged to feed strips of material intermittently over the bed, and a set of operating-tools actuated from said shafts and adapted to serrate the edges of the material, bend down the points or teeth of the serrated edges, dent the teeth longitudinally, and to separate the material transversely, substantially for the purpose set forth.

3. A machine for making antitacks, comprising a bed, means for feeding strips of material over the bed, a set of rotary punches for serrating the edges of said strip, means for bending the serrated edges, and means

for separating the material transversely between the successive teeth, substantially for the purpose set forth.

4. A machine for making antitacks, comprising a bed, means for feeding strips of material over the bed and means for serrating the edges thereof, a rotary bender-head adapted to engage the serrated edges and bend the teeth, and means for separating the strip transversely, substantially for the purpose set forth.

5. A machine for making antitacks, comprising a bed, a pair of parallel shafts supported at the respective sides of said bed, means for actuating said shafts from the source of power, a set of rollers arranged to feed strips of material intermittently over said bed, punchers and dies for serrating or cutting out the edges of said strip to form the points of the antitacks, a device for bending the points, and a knife for cutting or separating the strip transversely between the successive points, said feed-rollers, punchers, benders, and knife being in connection with, and simultaneously operated by, the said shafts, substantially for the purpose set forth.

6. A machine for making antitacks, comprising a bed, a pair of parallel shafts supported at the respective sides of said bed, means for actuating said shafts from the source of power, a set of rollers arranged to feed strips of material intermittently over said bed, punchers and dies for serrating or cutting out the edges of said strip to form the points of the antitacks, a device for bending the points, dinters for crimping or denting the points, longitudinally, and a knife for separating or cutting the strip transversely between the successive points, said feed-rollers, punchers, benders, dinters and knife being in connection with, and simultaneously operated by, the said shafts, substantially for the purpose set forth.

7. A machine for making antitacks, comprising a bed, a pair of parallel shafts supported at the respective sides of said bed, means for actuating said shafts from the source of power, a set of rollers arranged to feed strips of material intermittently over said bed, punchers and dies for serrating or cutting out the edges of said strip to form the points of the antitacks, a device for bending the points, dinters for crimping or denting the points longitudinally, a printer for stamping the uncut portion of the material, and a knife for cutting or separating the strip transversely between the successive points, said feed-rollers, punchers, benders, dinters, printer, and knife being in connection with, and simultaneously operated by, the said shafts, substantially for the purpose set forth.

8. A machine for making antitacks, comprising a bed, a pair of parallel shafts, supported at the respective sides of the bed, means for actuating said shafts from the source of power, a set of rollers arranged to

feed strips of material intermittently over the bed, rotary puncher-heads, located upon said shafts, and provided with punches adapted to register with dies located upon the bed, whereby the material is notched at its edges, rotary bender-heads, also located upon said shafts, and adapted to intermittently engage and bend the notched edges of the material, a shear-plate located at the end of the bed, and a reciprocatory knife adapted to cut off that portion of the material strip which projects over the bed, with connections whereby said knife is operated from one of the shafts.

9. A machine for making antitacks, comprising a bed, a pair of parallel shafts supported at the respective ends of the bed, means for actuating said shafts, from the source of power, a set of rollers arranged to feed strips of material intermittently over the bed, rotary puncher-heads located upon said shafts, and provided with punchers adapted to register with dies located upon the bed, whereby the material is notched at its edges, rotary bender-heads also located upon said shafts and adapted to intermittently engage and bend the notched edges of the material, a shear-plate located at the end of the bed, and a reciprocatory knife adapted to cut off that portion of the material strip which projects over the bed, with connections whereby said knife is operated from one of the shafts, and a printing device adapted to print upon or stamp the uncut portion of the material strip, connected to the knife-arm and operated from the latter.

10. A machine for making antitacks, comprising a bed, a pair of parallel shafts supported at the respective sides of the bed, means for actuating said shafts from the source of power, a set of rollers arranged to feed strips of material intermittently over the bed, rotary puncher-heads, located upon said shafts and provided with punches adapted to register with dies located upon the bed, whereby the material is notched at its edges, rotary bender-heads also located upon said shafts, and adapted to intermittently engage and bend the notched edges of the material, a shear-plate located at the end of the bed and a reciprocatory knife adapted to cut off that portion of the material strip which projects over the bed, a spring for holding said knife with its edge normally above the shear-bar, and an eccentric located on one of said shafts and arranged to actuate the knife at regular intervals.

11. In a machine for making antitacks, the combination of a frame, a bed divided along its longitudinal center, with its lower surface provided with projections engaged in slots in said frame, set-screws for adjustably securing the bed-sections to the frame, right and left screw-threaded shafts running transversely of the bed-sections, whereby the latter may be separated and adjusted as desired, together with means for passing strips of material over

said bed, and a set of operating-tools for forming said strip into the desired shape and cutting it into sections.

12. In a machine for making antitacks, the combination of a frame, a bed divided along its longitudinal center, means for laterally adjusting the bed-sections to increase or diminish the width of the bed, a pair of parallel shafts supported from the respective bed-sections, a worm-shaft extending transversely of the bed-sections, and connected with a source of power, suitable gearing fast on said shafts, and engaged by said worm-shaft, and a set of operating-tools located upon said shafts and adapted to cut and bend the edges of a strip of sheet metal passed over said bed, together with a separating-knife actuated from one of said shafts, and adapted to cut the material into sections.
13. In a machine for making antitacks, the combination of a frame, a bed divided along its longitudinal center, means for laterally adjusting the bed-sections to increase or diminish the width of the bed, a pair of parallel shafts supported from the respective bed-sections, a worm-shaft extending transversely of the bed-sections and connected with a source of power, suitable gearing fast on said shafts, and engaged by said worm-shaft, and a set of operating-tools located upon said shafts and adapted to cut and bend the edges of a strip of sheet metal passed over said bed, means for feeding said strip intermittently, together with a separating-knife actuated from one of said shafts and adapted to cut the material into sections.

14. In a machine for making antitacks, the combination of a frame, a bed divided along its longitudinal center, means for laterally adjusting the bed-sections to increase or diminish the width of the bed, a pair of parallel shafts supported from the respective bed-sections, a worm-shaft extending transversely of the bed-sections and connected with a source of power, suitable gearing fast on said shafts and engaged by said worm-shaft, and a set of intermittently-acting operating-tools located upon said shafts and adapted to cut and bend the edges of a strip of sheet metal passed over said bed, means for feeding said strip intermittently, together with a separating-knife actuated from one of said shafts, and adapted to cut the material into sections.

15. In a machine for making antitacks, the combination of a frame, a bed divided along its longitudinal center, means for laterally adjusting the bed-sections to increase or diminish the width of the bed, a pair of parallel shafts supported from the respective bed-sections, a worm-shaft extending transversely of the bed-sections, and connected with a source of power, suitable gearing fast on said shafts and engaged by said worm-shaft, and a set of operating-tools located upon said shafts

and adapted to cut and bend the edges of a strip of sheet metal passed over said bed, a pair of feed-rollers for actuating said strip, an eccentric located on one of said shafts and connections adapted to be intermittently actuated by said eccentric, and to communicate their motion to said feed-rollers, together with a separating-knife actuated from one of said shafts, and adapted to cut the material into sections.

16. In a machine for making antitacks, a rotary puncher-head comprising a head-block adapted to be keyed to an actuating-shaft, and provided with recesses in its sides, punches removably secured in said recesses by set-screws, and a lateral disk removably secured to the recessed side of the puncher-head, and adapted to furnish a lateral support for the punches, substantially for the purpose set forth.

17. In a machine for making antitacks, a bender-head comprising a head-block adapted to be keyed to an actuating-shaft and provided with sockets in its periphery, arms movably engaged in said sockets and seated upon spring-cushions located therein, and rollers journaled to the outer ends of said arms, substantially for the purpose set forth.

18. In a machine for making antitacks, a bender-head comprising a head-block adapted to be keyed to an actuating-shaft and provided with sockets in its periphery, arms movably engaged in said sockets and seated upon spring-cushions located therein, and rollers journaled to the outer ends of said arms, substantially for the purpose set forth.

19. In a machine for making antitacks, a bender-head comprising a head-block adapted to be keyed to an actuating-shaft, and provided with sockets in its periphery, arms movably engaged in said sockets and provided with studs engaging in slots at the sides thereof, springs located in said sockets and adapted to force the arms outwardly, and rollers journaled to the outer ends of said arms, substantially for the purpose set forth.

20. In a machine for making antitacks, the combination of a rotary bender-head provided with a laterally-projecting hub, a spring-retracted denter-bar located adjacent thereto, and provided at its rear end with a curved plate or sector, and one or more rollers journaled to an arm or arms projecting from the hub of the bender-head, and adapted to impinge upon said curved plate to actuate the denter-bar, substantially for the purpose set forth.

In testimony whereof I affix my signature in the presence of two witnesses.
